CURVED JALOUSIE WINDOW

Phillip Graham, 2825 Glenmore Ave., Pittsburgh, Pa.

Filed Mar. 12, 1959, Ser. No. 54,956

Term of patent 14 years

(Cl. D13—1)

FIG. 1 is a perspective view taken from the outside of a curved jalousie window showing my new design, the window panes being in open positions;

FIG. 2 is a sectional view thereof taken along line 2—2 of FIG. 1;

FIG. 3 is a fragmentary elevational view taken from a low position outside of the window looking towards the outer edges of the panes in the direction of their planes.

The essential features of my design reside in the portions shown in full lines.

I claim:

The ornamental design for curved jalousie window, substantially as shown and described.
